FINGER RING

Mason M. Sager, Chicago, Ill.

Application April 19, 1954, Serial No. 30,085

Term of patent 14 years

(Cl. D45—10)

FIG. 1

FIG. 2

FIG. 3

To all whom it may concern:

Be it known that I, Mason M. Sager, a citizen of the United States and resident of Chicago, in the county of Cook and State of Illinois, have invented a new, original, and ornamental Design for a Finger Ring, of which the following is a specification, reference being had to the accompanying drawing, forming a part thereof.

In the drawing, Figure 1 is a perspective view of a finger ring showing my new design;

Figure 2 is a top plan view of the ring; and

Figure 3 is a side elevational view of the ring.

I claim:

The ornamental design for a finger ring, as shown.
